UNITED STATES PATENT OFFICE

JOSEPH B. STRAUSS, OF SAN FRANCISCO, CALIFORNIA

DESIGN FOR AN OVERHEAD STREET CROSSING

Application filed October 20, 1931. Serial No. 41,453. Term of patent 14 years.

To all whom it may concern:

Be it known that I, JOSEPH B. STRAUSS, a citizen of the United States of America, residing at San Francisco, in the county of San Francisco and State of California, have invented a new, original, and ornamental Design for Overhead Street Crossings, of which the following is a specification, reference being had to the accompanying drawings, forming a part thereof.

Fig. 1 is a front elevation of my design,
Fig. 2 is an end elevation of my design, and
Fig. 3 is a top plan view of my design.
I claim:

The ornamental design for an overhead street crossing, substantially as shown.

JOSEPH B. STRAUSS.
